DESIGN FOR AN AIRCRAFT

Alexander P. de Seversky, Asharoken Beach,
Northport, N. Y., assignor to Seversky Air-
craft Corporation, Farmingdale, N. Y., a corpo-
ration of Delaware

Application November 9, 1937, Serial No. 72,718

Term of patent 14 years

To all whom it may concern:

Be it known that I, Alexander P. de Seversky, a citizen of the United States, residing at Asharoken Beach, Northport, Suffolk County, State of New York, have invented a new, original, and ornamental Design for an Aircraft, of which the following is a specification, reference being had to the accompanying drawings, forming part thereof. In these drawings,

Fig. 1 is a front perspective view of the aircraft of my new design with the underneath-portion of the craft showing;

Fig. 2 is a front elevation of same;
Fig. 3 is a side elevation thereof;
Fig. 4 is a top, rear three-quarters view thereof,
and
Fig. 5 is a top plan view thereof.
I claim:
The ornamental design for an aircraft, sub-
stantially as shown.

ALEXANDER P. DE SEVERSKY.
